[57] CLAIM

The ornamental design for identification collar for containers, as shown and described.

DESCRIPTION

FIG. 1 is a perspective view of an identification collar for containers showing our new design;

FIG. 2 is a top plan view thereof;

FIG. 3 is a side elevational view thereof;

FIG. 4 is a bottom plan view thereof; and,

FIG. 5 is a perspective view thereof, with the collars shown stacked.

The broken line showing of the associated cylinder in FIG. 1 and ring in FIG. 5 is for illustrative purposes only and forms no part of the claimed design.

FIG. 1

FIG. 5

FIG. 2

FIG. 3

FIG. 4
